ELECTRIC-ARC LAMP.

1,159,383.

Specification of Letters Patent.

Patented Nov. 9, 1915.

Application filed March 7, 1910. Serial No. 547,824.

To all whom it may concern:

Be it known that I, RICHARD HOLSTEN, a subject of the German Emperor, and residing at Charlottenburg, near Berlin, Germany, have invented certain new and useful Improvements in Electric-Arc Lamps, of which the following is a specification.

My invention relates to electric arc-lamps, whose arcs are not maintained by electrodes in the form of rods, but by solid, liquid or gaseous substances which are supplied in the form of powder, vapor or gases to between electrodes serving substantially only for supplying the current.

It has long been known in the art that the arc in electric arc lamps may be maintained by supplying solid combustibles in powder form, or liquid combustibles between two solid and stationary electrodes. The reason why lamps of this character have not been used more frequently in practice appears to be that in such lamps, as heretofore used, the combustible is supplied by certain mechanisms which, however, respond only to the fluctuations of the current. In such lamps the supply of combustibles is not proportional to their consumption, which latter aside from being dependent upon the fluctuations of the current, depends upon several other conditions, affecting and varying the temperature of the arc and thus the degree of vaporization of fuel. One of these conditions is the motion of the surrounding air, another the chemical uniformity of the mixture of combustibles supplied to the arc which cannot be completely maintained, however careful the material may be prepared. In view of these above facts, I particularly consider it a disadvantage to have both the electrodes fixed, and the conveying of combustibles controlled by the fluctuations of current as has been done heretofore.

The principal object of my invention is to remedy these defects.

According to my invention, at least one electrode is to be movable—for instance in the form of a suspended solenoid core—to have the well known regulation in dependence on the fluctuations of current or voltage. Thus in particular all the disadvantages of lamps with fixed electrodes are

avoided, owing to irregular supply of combustible and to irregular evaporation of the latter.

According to my invention the combustible is preferably supplied in dependence on the electrical occurrences. This can be done by mechanically or electromagnetically releasing the feeding device. However, it is not possible thereby to avoid an over- or an under-feed of combustible, for not all the fluctuations of current and voltage are due to varying consumption of combustible. In the case of over supply either too much combustible is consumed or insulating residues are formed which render re-ignition difficult; also, combustible which is left lying on one electrode may prevent the electrodes contacting with each other and, consequently, the restriking of the arc. When too little combustible is supplied, on the contrary, the arc is too small and emits too little light. I avoid these defects by supplying the combustible according to its consumption. Such a regulation is obtained, for example by supplying the combustible at definite intervals. The irregularities, caused thereby are only small and are readily equalized by the lamp.

The supply of combustible will be most perfect, however, when it is in dependence on the length of the arc. It is then made dependent on a quite definite position of electrode. This mode of regulation combines the advantages of the two above described methods of regulation; for the length of arc is dependent both on the existing voltage and on the electrical conditions, as well as on the combustible present, and thus on the quantity of combustible which is supplied mechanically. Thus, when the lamp is regulated according to the length of arc both the exterior influences and the occurrences in the lamp itself are taken into account. Consequently, a lamp regulated in this manner burns with very small fluctuations in the strength of the light.

In the accompanying drawing, I have illustrated how my invention may be reduced to practice.

In these drawings: Figure 1 is a sectional elevation showing part of one form of lamp

comprising superposed electrodes, the upper of which is movable and serves as conduit for the combustible; Fig. 2 is a like view showing part of a modified form, in which the combustible is supplied in a lateral tube, Fig. 3 shows in more or less diagrammatical form partly in sectional elevation and partly in perspective another form of lamp, in which two kinds of combustible are supplied to between the electrodes with the aid of the devices shown in Figs. 1 and 2.

Referring to the drawings, in all the views A designates the bottom electrode, B the top electrode, C the regulating coil requisite for the lamp and which may have any suitable form known in the art, and D the feed hopper arranged under the outlet E of the receptacle for the combustible. The rest of the receptacle itself is not represented in the drawings but is to be thought of as located above the outlet E.

I arrange the receptacle for the combustible and the feed mechanism, which is more particularly described hereinafter, stationary, in contradistinction to the third known arrangement referred to above in which the movable electrode serves as receptacle for the combustible. This is very important, because in this manner I make the regulating device independent of the constantly varying weight of the quantity of combustible and diminish the amount of energy of the lamp requisite for its regulation, as only the feed mechanism has to be moved. In addition, without altering the regulating mechanism I can put any desired quantity of combustible into the lamp; also, considerable changes in the specific weight of the combustible require only immaterial, if any, changes in the regulating mechanism. A further advantage of this arrangement is that, owing to the receptacle being at rest and in spite of the electrode supplying the combustible being movable, almost any of the well known conveying and feeding devices may be employed for discharging the combustible from the receptacle.

In the drawings the following are indicated as the most useful arrangements: In Fig. 1 a feed-wheel *f*, in Fig. 3 a conveyer screw *m*, as well as a hopper *d* having a tapper *t*, but equivalent feeding means known in the art may be employed. The arrangement of the feed hopper *d* having a tapper according to Fig. 3 is particularly suitable, because the hopper itself can serve as storage receptacle; and the means for causing discharge therefrom consists only of the small hammer *t*. An ordinary butterfly valve *u* suffices here for regulating the outflow, while in the other cases the regulation of the outflow is more difficult. For operating the tapper I provide a relay *r*₂ and a spring *v* which actuate a rocking armature *s*₂ carrying the hammer *t*. The coil *r*₂ is

connected to the points F and G and is energized simultaneously with the relay *r*₁ which is described hereinafter; it may, of course, be connected in series with the relay *r*₁.

The combustible may be supplied by the feeding mechanism to the arc either through the electrodes, or through a tube or channel leading laterally of the electrode to the arc. The former arrangement is shown in Fig. 1, in which the top electrode B has through its entire length a bore *a* in which the funnel D is inserted and secured. *b* designates an iron jacket around the non-magnetic portion B of the electrode. Fig. 2 shows the combustible supplied laterally of the electrode. The means for this preferably comprise a funnel *k* which surrounds the top electrode with about 1 to 3 mm. clearance immediately above the arc and is simultaneously formed as a so-called economizer. There is no danger of the funnel becoming stopped up at *j* because the electrode is constantly in motion.

The feeding mechanism shown in Fig. 1 is actuated periodically, with the intermediary of the movable electrode, according to my invention by means of a pawl secured to said electrode; this pawl may act on the feeding mechanism by direct engagement with it or it may indirectly release mechanical or electromechanical auxiliary devices (not shown). Fig. 1 shows the direct engagement. In this form the funnel D carries an arm *e* having a pawl *e*₁ which engages the blades *h* of the feed-wheel *f* when the electrode B descends and thus rotates the wheel clockwise step by step. In this manner the required quantity of combustible is thrown out of the receptacle E through the outlet *g*. A yieldingly supported retaining pawl *c* engaging behind blades *h* after each stroke prevents reverse movement of the wheel, and by the elasticity of its yielding support also prevents overthrowing.

The above described direct drive is the simplest form of regulation, but it increases the consumption of current in the lamp because a considerable amount of power is necessary for driving the feeding mechanism. By employing mechanical or electromechanical auxiliary devices the movable electrode is materially relieved; it then moves only a small releasing lever or a switch, which in turn controls a clockwork or a relay, fed from the electric supply system. In this manner the current consumption of the lamp itself and the load on the main coil of the lamp is reduced, and also greater freedom of movement of the movable electrode is materially increased and thereby the sensitiveness of the lamp to regulation; in addition, it is possible to place any desired amount of auxiliary sources of power for moving the feeding mechanism

into control of such mechanism. This arrangement is illustrated in Fig. 3. The feed screw m is operated by a relay r_1 comprising an armature s_1 which carries a bent arm w which forms the feeding pawl for ratchet wheel z . This wheel is secured on the shaft of the worm m and prevented from overthrowing by retaining pawl h . The relay r_1 is energized as soon as a stop or abutment n , 5 which is secured on but insulated from the electrode B , depresses the lever o which is located in its track and thereby opens the contact at H between the two electrically conducting parts p and q of the switch C' . 10 The abutment n as will be clear from Fig. 3 is beveled at its end with which it cooperates with lever o , also beveled, but in the opposite direction. When abutment n 15 is descended depresses the rear end of lever o to break the contact at H , it will on descending far enough, eventually slide past lever o , so that the latter falls back into normal position. Abutment n descends past lever o when the lamp is at rest where the 20 electrodes contact. Then if the lamp is lighted and electrode B drawn upward to form the arc, abutment n can slide past lever o on the beveled surface. So long as there 25 is sufficient combustible at the arc, the latter is regulated by the upward and downward movement of the electrode B as usual, without thereby causing the feeding of combustible. However, as the latter is consumed the electrode gradually sinks lower and lower 30 until abutment n engages with and depresses lever o , p , lifting it for a moment at H , which sends a current impulse through relays r_1 , and r_2 . This in turn operates the feeding mechanism and the necessary 35 amount of combustible supplied thereby causes electrode B to again rise, abutment n thereby rising from lever o . The switch arm p is insulated from the member o . The relay is then energized in the following 40 circuit: positive feeder 1, electrodes A, B and the arc therebetween, conductor 2, lamp coil C, conductors 3, 4, relay r_1 , conductor 5 and negative feeder 6. The short-circuiting connection by way of the parts p , q is provided 45 for preventing the relay coil being permanently energized and the loss of energy caused thereby. Consequently, the relay coil 50 is generally shunted and is only energized at the time of, and for the purpose of, regulation. 55

As material for the electrodes A and B, according to tests which have been made both carbon and metal can be used, *i. e.* both a substance which is readily consumed by the arc and a substance which is practically incombustible. Also, one electrode may be combustible and the other incombustible. In all instances the means at the arc for supplying current may be so arranged that they 60 are consumed to only a small extent when

the lamp burns. The top electrode may, if desired, be made of copper with a liberal section of area. Copper as electrode, however, emits but little light owing to its good conductivity, which keeps the temperature 70 of the arc low. For this reason substances which of less heat conductivity are preferable as electrodes, and if necessary such substances may have metal insertions x (Fig. 3) for increasing the electrical conductivity, 75 which insertions must be limited however to the absolutely necessary amount.

With regard to the bottom electrode in a lamp having vertically superposed carbons, care should be taken that this current-supplying member has a larger cross-section than the top current-supplying member, first in order that the combustible which is thrown out does not fall past it, and second, in order that whatever portion of the electrode may be consumed by combustion may burn away with as flat a tip as possible. Bottom electrodes which do not readily burn away are preferably filed flat or hollowed out like a trough as shown at y_2 in 80 Fig. 2 and y_3 in Fig. 3, whereas metallic electrodes may be recessed as shown at y_1 in Fig. 1. The supply of the powder should be sufficient so that the least possible amount of the bottom electrode burns away even 85 when it is composed of a combustible substance; it should serve only as support or plate for the admixtures for making the arc luminous. When an ordinary carbon is used as lower electrode the burning flat will 90 be aided by having it copper-plated, as indicated at l in Fig. 3. When the means for supplying current to the arc is used as catch plate it must be connected to the positive 95 pole of the system, as shown in Fig. 3. 100

As powdered combustible, both pure carbon may be used and any desired mixture of carbon with other substances which emit strong light, such as metallic salts and the like. A lamp according to my invention 110 constitutes a very simple apparatus for use in testing the strength of light and the effect of various kinds of combustibles. Different kinds of combustibles may be mixed in the lamp itself, since several devices for supplying combustible can be combined in it without difficulty, such a combination being shown in Fig. 3, in which the arrangements described above with reference to Figs. 1 115 and 2 are employed simultaneously. 120

Instead of pouring the combustible to the arc as described above, it might be injected or blown into it. Neither of such modes of operation can be recommended, however. Pouring it has the very great advantage that 125 the arc is not disturbed, whereas in the other methods referred to disturbance of the arc cannot be helped. The method of pouring is used to best advantage when, as shown, superposed electrodes and a tubular upper 130

electrode are employed and the combustible is poured through the middle of the latter onto the bottom electrode. For, owing to the tubular shape of the electrode, the arc occupies the position represented in Figs. 5 1 and 3, namely, it is located so far to one side that the descending combustible does not disturb it. The fallen combustible is first fused and then gradually vaporized, 10 and assumes the form of vapor only in the arc.

I claim:

1. In an electric arc-lamp of the character described, the combination, with an electrode, of a movable electrode, a receptacle containing a combustible, feeding means for supplying the combustible to between said electrodes for maintaining an arc therebetween, means for moving said movable electrode in dependence on the electrical occurrences in the lamp, and means for actuating said feeding means in dependence on the consumption of combustible in the arc.

2. In an electric arc-lamp of the character described, the combination, with an electrode, of a movable electrode, a receptacle containing a combustible, feeding means for supplying the combustible to between said electrodes for maintaining an arc therebetween, means for moving said movable electrode in dependence on the electrical occurrences in the lamp, and means for actuating said feeding means in dependence on the length of the arc.

3. In an electric arc-lamp of the character described, the combination, with an electrode, of a movable electrode, a receptacle containing a combustible, feeding means for supplying the combustible to between said electrodes for maintaining an arc therebetween, means for moving said movable electrode in dependence on the electrical occurrences in the lamp, and means for actuating said feeding means in dependence on the position of the movable electrode.

4. In an electric arc-lamp of the character described, the combination, with an electrode, of a movable electrode, a fixed receptacle containing a combustible, feeding mechanism fixed in the lamp for supplying the combustible through said movable electrode to between said electrodes for maintaining an arc therebetween, means for actuating said feeding mechanism in dependence on the consumption of combustible in the arc, and means for moving said movable electrode in dependence on the electrical occurrences in the lamp.

5. In an electric arc-lamp of the character described, the combination, with an electrode, of a movable electrode, a receptacle containing a combustible fixed in the lamp, feeding mechanism fixed in the lamp for supplying the combustible to between said electrodes for maintaining an arc there-

tween, means attached to said movable electrode for periodically actuating said feeding mechanism, and means for moving said movable electrode in dependence on the electrical occurrences in the lamp.

6. In an electric arc-lamp of the character described, the combination, with an electrode, of a movable electrode, an economizer having a conical recess in the top thereof surrounding one of the electrodes with clearance, a receptacle containing a combustible, feeding means for supplying the combustible by way of said economizer to between said electrodes for maintaining an arc therebetween, and means for moving said movable electrode in dependence on the electrical occurrences in the lamp.

7. In an electric arc-lamp of the character described, the combination, with an electrode, of a movable electrode arranged over the same, a funnel-shaped economizer surrounding the movable electrode with clearance, a receptacle containing a combustible, feeding means for supplying the combustible by way of said economizer to between said electrodes for maintaining an arc therebetween, and means for moving said movable electrode in dependence on the electrical occurrences in the lamp.

8. In an electric arc-lamp of the character described, the combination, with an electrode, of a movable electrode, a funnel-shaped economizer surrounding the movable electrode with clearance, a hopper, containing a combustible, for supplying the latter by way of said economizer to between said electrodes for maintaining an arc therebetween, a tapper for knocking said hopper, electromagnetic means for actuating said tapper in dependence on the electrical occurrences in the lamp, and means for moving said movable electrode in dependence on the electrical occurrences in the lamp, said hopper having a conduit arranged laterally of the movable electrode and leading to said economizer.

9. In an electric arc-lamp of the character described, the combination, with an electrode, of a movable electrode, a receptacle containing a combustible fixed in the lamp, feeding mechanism fixed in the lamp for supplying the combustible to between said electrodes for maintaining an arc therebetween, means comprising a stop attached to said movable electrode, a switch actuated by said stop, a relay controlled by said switch for periodically actuating said feeding mechanism, and means for moving said movable electrode in dependence on the electrical occurrences in the lamp.

10. In an electric arc-lamp of the character described, the combination, with an electrode, of a movable electrode, a receptacle containing a combustible fixed in the lamp, feeding mechanism fixed in the lamp
